MAGNETIC INSERT FOR SEALING HEADS

Joseph C. Nash, Fairmont, W. Va., assignor to
Westinghouse Electric Corporation, East Pitts-
burgh, Pa., a corporation of Pennsylvania

Application November 28, 1951, Serial No. 258,720

3 Claims. (Cl. 49—2)

1

This invention relates to sealing machines and, more particularly, to a magnetic insert for a sealing head of a butt-sealing machine.

In the butt-sealing of miniature incandescent lamps on automatic high speed machines, the lamp bulb or envelope with the dome down is inserted into a bulb rest of a sealing head and secured therein either by a mechanical bulb holder which grips the bulb neck or by a vacuum line inside the sealing head shaft extending from the bottom of the bulb rest. The lamp mount is loaded into the bulb and centered therein by the gravitational weight of the mount and the pre-formed external portions of the mount lead wires which grip the open end of the bulb neck. An exhaust tubulation suitably the same diameter as the bulb neck is axially aligned with the neck by a tubulation holder and then sealed to the neck with the lead wires therebetween. During sealing the seal is formed to the desired constricted configuration for basing.

Due to the rotation of the sealing heads between stationary sealing fires at the sealing stations, the gravitational force of the light lamp mount is insufficient to prevent shifting of the mount from its axial position within the bulb. As a result off-center mounts are often sealed into the bulb. In the case of glow lamps, it is necessary to recenter the lamp mount after sealing by sharp blows are shocks from instruments such as a hammer. A glow lamp is an electrical discharge device which produces light when an inert gas, usually neon, is ionized by the application of a voltage between two electron-emissive coated electrodes and passes current. This re-alignment method is expensive and often results in shrinkage, such as cracked envelopes and seals.

Hence it has been found advantageous, according to my invention, to provide a magnetic insert within the bulb rest of the sealing head which will maintain the lamp mount by the force of magnetism on the mount electrodes in a centered position within the bulb, thereby preventing the shifting of the mount in the rotating sealing stations of the butt-sealing machine. Sealed lamps having off-center mounts are thereby eliminated. Realignment by the shock method is not necessary and resultant lamp shrinkage is reduced.

In its general aspect, the present invention has as its objective the elimination of the disadvantages and defects of the prior art sealing heads for a butt-sealing machine.

The principal object of the present invention is a magnetic insert for a bulb rest which holds

2

a miniature lamp mount centered in the bulb in the rotating sealing stations of a butt-sealing machine.

A specific object is the elimination of sealed lamps having off-center mounts.

Another object is the elimination of the shock method for realigning off-center mounts in sealed miniature lamps.

Other objects of the invention will appear to those skilled in the art to which it appertains as the description thereof proceeds, both by direct recitation thereof and by implication from the context.

Referring to the accompanying drawings, in which like numerals of reference indicate similar parts throughout the several views:

Fig. 1 is a side elevational view of a sealing head of a miniature lamp butt-sealing machine where-in my invention is embodied;

Fig. 2 is an axial sectional view of a head, on the line II—II of Fig. 1, in the direction of the arrows;

Fig. 3 is a plan view of the sealing head of Fig. 1, showing the tubulation holder assembly;

Fig. 4 is a side elevational view of a miniature lamp such as a glow lamp;

Fig. 5 is an exploded elevational view of a bulb, a mount and an exhaust tubulation for the glow lamp of Fig. 4;

Fig. 6 is an elevational view, with parts in axial section, of a portion of the sealing head of Fig. 1 during sealing;

Fig. 7 is a view similar to Fig. 6, showing the formation of the tubulation constriction at the end of the sealing operation.

Sealing head

Referring to the drawings in detail, and particularly to Figs. 1, 2 and 3, a sealing head for a miniature lamp butt-sealing machine is designated by the reference numeral 10. This head, as shown in Figs. 1 and 2, has a hollow spindle 12 which is rotatable within a bushing 14 in a table 16 of the machine 10. On the lower end of the spindle a suitable rotating means, such as a gear wheel 18, is secured as by a set screw. Near the upper end of said spindle the hub 20 of a bottom yoke 22 is secured thereto as by a set screw not shown.

Between the hub 20 and the table 16 a thrust bearing 24 is provided on spindle 12. On the upper end of spindle 12 and overlying yoke 22, a holding collar 25 is affixed, as by a screw shown in Fig. 2.

Slidably vertically within a bushing 26 (Fig.

1) in the upper portion of spindle 12 is a sealing head shaft 28, the upper end of which projects beyond the collar 25 and the lower end of which projects below spindle 12 in table 16. On the lower end of shaft 28, adjustable cam track engagement means, such as a bolt 30, shown in Fig. 1, screwed into the threaded end of the shaft 28 and having a set-nut 32, is provided for engagement with a cam track 34 of the sealing machine 10. The shaft 28 has a reduced section on its upper end over which fits an L-shaped connector link 36 for transmitting vertical motion, as hereinafter described. The link 36 is affixed to shaft 28 as by a set screw through its hub portion, shown in Fig. 2.

The yoke 22 has socketed end portions 38 and 40 (Fig. 1) for mounting sealing head guide rods 42 and 44, respectively, by securing therein the reduced lower portions of said rods, as by set screws, shown in Fig. 1. On the upper reduced portions of rods 42 and 44, a horizontal forward portion 46 of an upper yoke or brace 48 of generally T-shaped configuration in plan is affixed as by set screws.

This brace 48 has a horizontal rearward portion 50 extending perpendicular to portion 46 and provided with an upper offset flange or hub 52 on its rearward end. A cup-like bulb rest 54, suitably of non-magnetic material, such as brass, has a magnetic insert 56, constructed in accordance with my invention, secured therein as by a set screw, shown in Fig. 2, and a rod-like lower portion 58. The latter portion is secured in a suitable hole in the horizontal portion 46 of the brace 48 at any desired elevation as by a set screw. Near hub 52 a suitable hole is provided in rearward portion 50 of brace 48 for securing therein a tubulation holder gear box tube 60, as shown in Fig. 2. A similar hole is provided in hub 52 for like attachment therein of a bulb holder gear box tube 62. Rotatable within tube 62 and projecting from both ends is a bulb holder shaft 64. A bulb holder assembly 66 is mounted on the upper end of tube 62 and has a spur gear 68 pinned to shaft 64, as shown in Fig. 2. A vertical slot 70 is provided in the upper end of shaft 64. A tubulation holder assembly 72, similar to bulb holder assembly 66, has a spur gear 74 carrying a pin 76 slidably in slot 70. Hence the assembly 72 is thereby slidable vertically on shaft 64.

On the lower end of tube 62 a spring retainer mounting plate 76 is secured, as by a set screw shown in Fig. 2. Below and abutting plate 76 on tube 62, and attached to shaft 64 as by a set screw is a movable handle 78 (Fig. 1) for simultaneously opening and closing the bulb holder assembly 66 and the tubulation holder assembly 72. An adjacent stationary handle 80 is secured, as shown in Figs. 1 and 3, to the lower portion of sealing head guide rod 42 to provide a stationary finger grip toward which movable handle 78 is to be squeezed. A collar 82 pinned to the lower extremity of shaft 64 has a torsion recovery spring 84 thereabout for returning assemblies 66 and 72 to their normally closed positions. The upper end of spring 84 is confined in a suitable vertical hole in the handle 78. The lower end of spring 84 is secured in a suitable lateral hole in a spring retainer plate 86 depending from a side face of plate 76 and secured thereto as by a screw as shown in Fig. 1.

This tubulation holder gear box tube 60 extends upwardly from rearward portion 50 of brace 48 through a suitable hole in the bulb holder as-

sembly 66 and downwardly from portion 50 through a hole in the spring retainer mounting plate 76. As shown in Fig. 2, both assembly 66 and plate 76 are secured to tube 60 as by set screws. Slidable within tube 60 is a tubulation holder shaft 88 the upper end of which is secured as by a set screw to the tubulation holder assembly 72. The upper end of tube 60 supports said assembly. Affixed to the lower end of shaft 88, as by a set screw shown in Fig. 2, is a spool 90 engaged by fork 92 of connecting link 36 and thereby vertically moving said assembly 72. Between spool 90 and plate 76 a compression spring 93 is provided on the lower end of tube 60 and shaft 88 to return the shaft 88 to normally lower position within the tube 60.

Tubulation holder assembly

As shown in Figs. 1 and 3, this tubulation holder assembly 72 comprises a gear box 94, a gear box cover 96, a rear rack 98 slidable in the box 94 and engageable with spur gear 74, and a front rack 100 also slidable in said box and engageable with said gear. Tubulation holder arms 102 and 104 extend from racks 98 and 100, respectively, for securing a tubulation 105 therebetween. As shown in Fig. 1, pins 106 and 108 project vertically from the forward portions of arms 102 and 104, respectively, and support spring 110 which produces the desired tension on said tubulation 105.

Bulb holder assembly

The bulb holder assembly 66 is similar to assembly 72 except the pins and cooperating spring 35 are not provided on its arms 112 and 114. Recesses 118 and 120 in the respective arms, shown in Figs. 1, 6 and 7 are tapered to fit the external portions of lead wires 122 and 124 of a mount 126 for a glow lamp 128. This assembly 66 has a gear box 130 (Fig. 2) and a cover 132, racks 134 and 136 from which bulb holder arms 112 and 114 respectively extend and which are engageable by the spur gear 68 on shaft 64.

The glow lamp 128 shown in Fig. 4 has a bulb 45 138 sealed to the mount 126 and the tubulation 105 and is provided with an inert gas fill such as neon and a base 140. The mount 126 comprises two electron-emissive coated electrodes suitably nickel or ferrous metal 142, 144, mounted 50 on the lead wires 122 and 124 which are held in spaced relation by a bead 146.

Magnetic insert

The magnetic insert 56 for the bulb rest 54 is 55 suitably formed of a permanent magnet alloy material having the following approximate composition and sold under the trademark "Alnico":

60	Metal	Composition Percentage
aluminum		11 to 13%
nickel		19 to 23%
cobalt		4.5 to 5.5%
iron		the balance

65

Operation

According to my invention, the butt-sealing machine operator grasps the movable handle 78 and the stationary handle 80 in one hand and squeezes them together, thereby opening the arms 112 and 114 of bulb holder assembly 66 and the arms 102 and 104 of the tubulation holder assembly 72 for loading. With her free hand the operator inserts a bulb 138 between the jaws 112 and

75

114 of assembly 66, inserts a mount 126 into the open end of bulb 138 and then positions a tubulation 105 on said bulb between the open jaws 102 and 104 of assembly 72. The insert 56 exerts a magnetic force on the nickel electrodes 142 and 144 of the mount 126, thereby centering said mount within said bulb 138.

As the sealing head 10 rotates between sealing fires 148 and 150, as shown in Fig. 6, the tubulation 105 and the open neck of the bulb 138 are sealed together with the lead wires 122 and 124 of the mount 126 therebetween. In the last sealing station of the machine 10, the sealing head shaft 28 is raised upwardly by the cam track 34. The connector link 36 raised the shaft 38 within the tube 60 and hence the tubulation holder assembly 72 upwardly, thereby forming a constriction in the plastic lower end of the tubulation 105, as shown in Fig. 7.

It will be understood that during the rotation of the sealing head 10 through the various stations of the sealing machine, the insert 56 of my invention has securely held by the force of magnetism the electrodes 142 and 144, and hence the mount 126 of the lamp 128, in the desired axial alignment with the bulb 138 and tubulation 105. At the unloading station of the sealing machine the operator opens the jaws of the bulb holder assembly 66 and the tubulation holder assembly 72 by means of movable handle 78 and removes the tubulated lamp from the machine.

After a suitable automatic exhaust, which may comprise a bake, cathode sintering, electrode out-gassing and a suitable final fill, the lamp is tipped off in the constricted area of the tubulation 105 and a base 140 affixed thereto with a suitable cement.

Thus it will be seen from the foregoing description that the magnetic insert 56 for a bulb rest of a miniature lamp butt-sealing machine head has eliminated the disadvantages and defects of the prior art heads. My magnetic insert holds the miniature lamp mount, such as mount 126, centered in a bulb, such as bulb 138, in the rotating sealing stations of a butt-sealing machine. As a result sealed lamps having off-center mounts have been eliminated. No longer is it necessary to realign off-center mounts in sealed miniature lamps, such as glow lamp 128, by the shock method.

Although a preferred embodiment of my invention has been disclosed, it will be understood that modifications may be made within the spirit and scope of the appended claims.

I claim:

1. A sealing head for a miniature lamp butt sealing machine having a hollow spindle and a sealing head shaft therein, means for rotating said spindle and said sealing head shaft, means for vertically reciprocating said sealing head shaft within said spindle, a bottom yoke on said sealing head shaft, sealing head guide rods extending upwardly from end portions of said bottom yoke, an upper yoke on the upper portion of said rods and having a rearwardly projecting portion, a tubulation holder shaft tube and a bulb holder shaft tube carried on said rearwardly projecting portion of said yoke, a link secured to the bottom portion of said sealing head shaft, a tubulation holder shaft adjacent said sealing head shaft and reciprocably contained within said tubulation holder shaft tube, a spool carried by the lower end portion of said tubulation holder shaft for engagement with said link, a tubulation holder assembly secured to the upper portion of said tubulation holder shaft, said tubulation holder assembly including a tubulation holder spur gear on said bulb holder shaft and provided with a tubulation holder gear pin for engagement with said bulb holder shaft tube slot to permit vertical reciprocation of said tubulation holder assembly with said tubulation holder shaft and to permit rotation of said tubulation holder spur gear with said bulb holder shaft, a pair of tube holder racks for engagement with said tubulation holder spur gear, and a tubulation holder arm secured to each of said tubulation holder racks, a bulb holder shaft adjacent said tubulation holder shaft and rotatably contained within said bulb holder shaft tube, a bulb holder assembly secured to said bulb holder shaft, said bulb holder assembly having a bulb holder spur gear on said bulb holder shaft, a pair of bulb holder racks for engagement with said bulb holder spur gear, and a bulb holder arm secured to each of said bulb holder racks, means for limitedly rotating said bulb holder shaft, an adjustable cup-like bulb rest secured on said upper yoke directly beneath said bulb holder arms when in the closed position, and a magnetic insert within said rest.

2. A sealing head for a miniature lamp butt sealing machine having a hollow spindle and a sealing head shaft therein, means for rotating said spindle and said sealing head shaft, means for vertically reciprocating said sealing head shaft within said spindle, a bottom yoke on said sealing head shaft, sealing head guide rods extending upwardly from end portions of said bottom yoke, an upper yoke on the upper portion of said rods and having a rearwardly projecting portion, a tubulation holder shaft tube and a bulb holder shaft tube carried on said rearwardly projecting portion of said yoke, a link secured to the bottom portion of said sealing head shaft, a tubulation holder shaft adjacent said sealing head shaft and reciprocably contained within said tubulation holder shaft tube, a spool carried by the lower end portion of said tubulation holder shaft for engagement with said link, a tubulation holder assembly secured to the upper portion of said tubulation holder shaft, said tubulation holder assembly including a tubulation holder spur gear on said bulb holder shaft and provided with a tubulation holder gear pin for engagement with said bulb holder shaft tube slot to permit vertical reciprocation of said tubulation holder assembly with said tubulation holder shaft and to permit rotation of said tubulation holder spur gear with said bulb holder shaft, a pair of tube holder racks for engagement with said tubulation holder spur gear, and a tubulation holder arm secured to each of said tubulation holder racks, a bulb holder shaft adjacent said tubulation holder shaft and rotatably contained within said bulb holder shaft tube, a bulb holder assembly secured to said bulb holder shaft, said bulb holder assembly having a bulb holder spur gear on said bulb holder shaft, a pair of bulb holder racks for engagement with said bulb holder spur gear, and a bulb holder arm secured to each of said bulb holder racks, means for limitedly rotating said bulb holder shaft, an adjustable cup-like bulb rest secured on said upper yoke directly beneath said bulb holder arms when in the closed position, and a magnetic insert within said rest.

3. A sealing head for a miniature lamp butt sealing machine having a hollow spindle and a sealing head shaft therein, means for rotating said spindle and said sealing head shaft, means for vertically reciprocating said sealing head shaft within said spindle, a bottom yoke on said sealing head shaft, sealing head guide rods extending upwardly from end portions of said bottom yoke, an upper yoke on the upper portion of said rods and having a rearwardly projecting portion, a tubulation holder shaft tube and a bulb holder shaft tube carried on said rearwardly projecting portion of said yoke, a link secured to the bottom portion of said sealing head shaft, a tubulation holder shaft adjacent said sealing head shaft and reciprocably contained within said tubulation holder shaft tube, a spool carried by the lower end portion of said tubulation holder shaft for engagement with said link, a tubulation holder assembly secured to the upper portion of said tubulation holder shaft, said tubulation holder assembly including a tubulation holder spur gear on said bulb holder shaft and provided with a tubulation holder gear pin for engagement with said bulb holder shaft tube slot to permit vertical reciprocation of said tubulation holder assembly with said tubulation holder shaft and to permit rotation of said tubulation holder spur gear with said bulb holder shaft, a pair of tube holder racks for engagement with said tubulation holder spur gear, and a tubulation holder arm secured to each of said tubulation holder racks, a bulb holder shaft adjacent said tubulation holder shaft and rotatably contained within said bulb holder shaft tube, a bulb holder assembly secured to said bulb holder shaft, said bulb holder assembly having a bulb holder spur gear on said bulb holder shaft, a pair of bulb holder racks for engagement with said bulb holder spur gear, and a bulb holder arm secured to each of said bulb holder racks, means for limitedly rotating said bulb holder shaft, an adjustable cup-like bulb rest secured on said upper yoke directly beneath said bulb holder arms when in the closed position, and a magnetic insert within said rest.

portion of said tubulation holder shaft, a bulb holder shaft adjacent said tubulation holder shaft and rotatably contained within said bulb holder shaft tube, a bulb holder assembly secured to said bulb holder shaft, said bulb holder assembly having a bulb holder spur gear on said bulb holder shaft, a pair of bulb holder racks for engagement with said bulb holder spur gear, and a bulb holder arm secured to each of said bulb holder racks, means for limitedly rotating said bulb holder shaft, an adjustable cup-like bulb rest secured on said upper yoke directly beneath said bulb holder arms when in the closed position, and a magnetic insert within said rest.

7
 holder shaft tube being provided with a bulb holder shaft tube slot in its upper end, a spring retainer mounting plate secured on the lower portion of said tubes, a link secured to the bottom portion of said sealing head shaft, a tubulation holder shaft adjacent said sealing head shaft and reciprocably contained within said tubulation holder shaft tube, a spool carried by the lower end portion of said tubulation holder shaft for engagement with said link, a tubulation holder assembly secured to the upper portion of said tubulation holder shaft, said tubulation holder assembly including a tubulation holder spur gear on said bulb holder shaft and provided with a tubulation holder gear pin for engagement with said bulb holder shaft tube slot to permit vertical reciprocation of said tubulation holder assembly with said tubulation holder shaft and to permit rotation of said tubulation holder spur gear with said bulb holder shaft, a pair of tube holder racks for engagement with said tubulation holder spur gear, and a tubulation holder arm secured to each of said tubulation holder racks, compression means on said tubulation holder shaft for returning said tubulation holder assembly to the normally lower
